UNITED STATES PATENT OFFICE.

AUGUST GROENIG, OF HOLLOWAY, MINNESOTA.

RUNNING-GEAR FOR AUTOMOBILES.

No. 854,210.

Specification of Letters Patent.

Patented May 21, 1907.

Application filed May 7, 1906. Serial No. 316,493.

To all whom it may concern:

Be it known that I, AUGUST GROENIG, a citizen of the United States, residing at Holloway, in the county of Swift and State of Minnesota, have invented certain new and useful Improvements in Running-Gear for Automobiles; and I do hereby declare the following to be a full, clear, and exact description of the invention, such as will enable others skilled in the art to which it appertains to make and use the same.

My invention relates to running gears for automobiles and is directed particularly to the improvement of the pivotal connection between the front or steering wheels and the coöperating axle or connecting frame.

The invention consists of the novel devices and combinations of devices hereinafter described and defined in the claims.

20 The invention is illustrated in the accompanying drawings, wherein like characters indicate like parts throughout the several views.

Referring to the drawings, Figure 1 is a 25 plan view, showing the front axle of an automobile or similar vehicle, and showing the wheels pivotally connected thereto in accordance with my invention. Fig. 2 is a view of the parts shown in Fig. 1, principally in elevation, with some parts sectioned on the line $x^2 x^3$ of Fig. 1. Fig. 3 is a detail taken in section on the line $x^3 x^3$ of Fig. 2, some parts being removed; and Fig. 4 is an elevation of the parts shown in Fig. 3, with some parts 30 sectioned on the line $x^1 x^4$ of Fig. 3.

The numeral 1 indicates a yoke-like axle, the up-turned ends of which are formed with sleeves 2 in which are rigidly secured bearing sleeves 3 having, at their outer extremities, 40 vertically spaced prongs or yoke-like extensions 4. Quite large bearing collars 5 surround the yokes 4 and are pivotally connected thereto by vertically extended trunnions 6 secured to the prongs of said yokes and working in seats in the said collars. These bearing collars 5 are thus pivoted for oscillatory movements on vertical axes, but are held 45 against rotary movement.

The wheels 7 are provided with large hubs 50 8 that are journaled on the bearing collars 5. At their outer ends, the hubs 8 are, as shown, provided with integrally formed heads 9 that run against the outer edges of the respective bearing collars 5. Ring-like nuts 10 which 55 have threaded engagement with the inner

extremities of the hubs 8, engage the inner extremities of the bearing collars 5 and hold the wheels in working position thereon, while permitting the free rotation thereof.

The heads 9 of the hubs 8 are formed with 60 inwardly projecting collars or annular flanges 11 which, in turn, are formed with diametrically opposite slots 12; which slots extend across a vertical plane intersecting the axes of the corresponding trunnions 6. 65

Short driving shafts 13 are journaled in and extend through the non-rotary bearing sleeves 3. At their outwardly extended ends, the shafts 13 are provided with heads 14 that are equipped with diametrically opposite rollers 15. These rollers 15 work in the slots 12 of the hub flange 11, and their axes lie in a common vertical plane with the axes of the corresponding trunnions 6. At their inner ends, the shafts 13 are provided 70 with sprockets 16 or other means for transmitting rotary motion to the said shafts. When the sprockets 16 are employed, power driven sprocket chains (not shown) will run over the said sprockets. 75

Arms 17 are rigidly secured to the bearing collars 5 and project inward and forward thereof. The two arms 17 are connected by a long link 18, so that the two bearing collars 5, and hence, the two steering wheels 7 will 80 be given parallel movements in the steering action, as indicated by full and dotted lines in Fig. 1. Any suitable steering connections for moving the link 18 may be provided. 85

As is evident, this improved device affords 90 means for transmitting motion to the steering wheels so that all four wheels of the vehicle may be used as traction wheels. The driving connections to the rear wheels may, of course, be of any suitable construction, 95 many satisfactory forms of which are well known.

When the wheels stand in the plane at a right angle to the axes of the shafts 13, there will be no movement of the wheel hubs 8 with respect to the roller equipped heads of the said shafts 13; but when the wheels stand in a plane at an oblique angle to the axes of the shafts 13, and the wheels are then rotated, the rollers 15 will travel over the 100 contacting surfaces of the slots 12. 105

The device described, while simple, strong and durable, will transmit motion to the wheels with but a very slight loss due to friction. 110

What I claim is:

1. The combination with an axle or trans-
verse support having, at its extremities,
bearing yokes, of bearing collars connected
5 to said yokes by vertical pivots, wheels hav-
ing their hubs journaled on the said bearing
collars, provided with inwardly projecting
annular flanges formed with slots, and driv-
ing shafts extended through said bearing
10 yokes and provided with driving projections
engaging the slots in the annular flanges of
the hubs of the respective wheels, substan-
tially as described.
2. The combination with an axle having
15 bearing sleeves 2 formed with non-rotary
yokes 4, of bearing collars 5 connected to
said yokes by vertical pivots, of wheels hav-

ing the hubs 8 journaled on said bearing col-
lars and provided with inwardly projected
annular flanges 11 formed with slots 12, driv-
ing shafts 13 extended through said sleeves 3
and provided, at their outer ends, with heads
14 having rollers 15 that work in the slots 12 of
said flanges 11, and means for imparting par-
allel oscillatory movements to said bearing 25
sleeves on their vertical pivots, substantially
as described.

In testimony whereof I affix my signature
in presence of two witnesses.

AUGUST GROENIG.
